US00D941206S

(12) **United States Design Patent** (10) **Patent No.:** **US D941,206 S**
(45) **Date of Patent:** **** Jan. 18, 2022**

(54) **VEHICLE FLOOR MAT**

(71) Applicant: **HYUNDAI MOBIS CO., LTD.**, Seoul (KR)

(72) Inventor: **Hyun Jin Chang**, Yongin-si (KR)

(73) Assignee: **HYUNDAI MOBIS CO., LTD.**, Seoul (KR)

(**) Term: **15 Years**

(21) Appl. No.: **29/795,118**

(22) Filed: **Jun. 16, 2021**

Related U.S. Application Data

(62) Division of application No. 29/708,259, filed on Oct. 4, 2019, now Pat. No. Des. 929,285.

(30) **Foreign Application Priority Data**

Apr. 18, 2019 (KR) 30-2019-0018226

(51) **LOC (13) Cl.** **12-16**

(52) **U.S. Cl.**

USPC **D12/203**
